(**) Term: **15 Years**

(57) **CLAIM**

(21) Appl. No.: **29/674,734**

The ornamental design for mobile phone holder for car air outlet, as shown and described.

(22) Filed: **Dec. 25, 2018**

DESCRIPTION

(51) LOC (12) Cl. **14-03**

FIG. 1 is a first perspective view of mobile phone holder for car air outlet showing the claimed new design;

(52) U.S. Cl. **USPC D14/253**

FIG. 2 is a second perspective view thereof;

(58) **Field of Classification Search**

FIG. 3 is a front elevation view thereof;

USPC D14/251-253, 440, 447; D12/415;
D8/354

FIG. 4 is a rear elevation view thereof.

CPC F16M 13/00; F16M 2200/00

FIG. 5 is a left side elevation view thereof;

See application file for complete search history.

FIG. 6 is a right side elevation view thereof;

(56) **References Cited**

FIG. 7 is a top plan view thereof;

U.S. PATENT DOCUMENTS

FIG. 8 is a bottom plan view thereof; and,
